CUP FILLING DEVICE

Giuseppe Sardo, Brooklyn, N. Y.

Application May 15, 1931, Serial No. 537,599

3 Claims. (Cl. 226—19)

This invention relates to cup filling devices and in particular to one arranged for use in the filling of paper cups with an ice or other like confection.

- 5 Ices heretofore have been dispensed in rigid paper cups or containers, the rigid container being necessary in order that the cup itself might be filled from a scoop or other filling utensil and the particular object of my invention is to provide a cup filling device in which may be placed a paper cup of thin construction, the invention 10 contemplating the supporting of the paper cup from both its upper, rolled edge and the bottom thereof so that the paper cup holding device may 15 be used as a scoop without danger of collapsing the paper cup held therein, the invention also contemplating the quick ejection of the filled cup so that dispensing of the ice cup may be readily performed.
- 20 A still further object of my invention is to provide a sanitary cup filling device in which the paper cup that is to be filled with the ice or confection is not handled by the dispenser, the cup being placed in the device and the same being 25 used as a scoop to fill the cup after which it is ejected by pressure on a part designed for that purpose.

Changes and variations may be made in the construction shown and described without departing from the principles of the invention or sacrificing its chief advantages; hence such invention is not to be confined to the structures shown in the accompanying drawing:

Figure 1 is a view in sectional elevation of a 30 cup filling device constructed in accordance with my invention.

Figure 2 is a top plan view of the cup filling device illustrated in Figure 1, and

Figure 3 is a fragmentary portion of the upper 40 end of a cup filling device employing a different method of supporting the rolled edge of a paper cup positioned in the filling device.

Referring to the drawing in detail, 5 indicates a cylindrical cup, preferably made of metal and having a closed bottom 6 therein. In the preferred form of my invention and in order to produce the device as cheaply as possible, the upper open end of the cup 7 may have rolled therein as at 8, an annular bead which forms a 45 shelf upon which rests the rolled edge 9 of the paper cup 10 to be positioned in the cup 5 preparatory to the filling of the same with an ice or like confection.

The cup 5 is provided with a horizontally extending, tubular handle 11, provided near its

outer end, with an under side opening 12, through which extends, an ejector spring arm 13. The inner end 14 of the spring arm is positioned within the tubular handle and presses against the inner wall of said handle as at 15, it being understood that the ejector spring arm is made of spring steel and can be flexed by the grip of the hand to bend the same up to the position illustrated in outline as at 16. The ejector spring arm in its exposed portion provides a hand hold 60 whereby it can be flexed as described. The end of the ejector spring arm 13 is secured in any suitable manner as at 17 to an ejector plate or disk 18 which normally rests and bears against the closed bottom 6 of the cup 5 by reason of the 65 tendency of the spring arm to open up due to its springy nature.

The ejector plate fits snugly in the bottom of the cup 5 and provides a support upon which rests the bottom 19 of the paper cup 10, the distance from the annular bead 8 of the cup to the upper surface of the ejector plate 18 being an important consideration inasmuch as the cup must be supported by itself so that it will not become distorted under the pressure of filling 70 during a scooping movement of the filling device in a can of ice or similar confection.

The bead 8 supports the rolled edge 9 at the upper end of the paper cup and prevents its collapse while the bottom of the paper cup is 75 supported flatly on the ejector plate 18 and consequently, the cup, being supported at two points, that is, its top and bottom, is prevented from collapsing or becoming so distorted at its bottom that its withdrawal from the filling device 80 is retarded.

The ejector spring arm 13 operates through a suitable slot 20 provided in the wall of the cup 5 and extending from the bottom thereof upwardly to a point 21 of sufficient height to permit 85 operation of the ejector plate to raise the filled cup 10 sufficiently above the level of the top of the cup 5 to enable it to be removed by the hand of the one dispensing the confection and, as illustrated in outline, in Figure 1.

It will be noted that the handle 11 is soldered or otherwise secured to the cup 5 and when a filling operation is performed, the handle 11 only is grasped so that there is no tendency to lift the ejector plate during a filling operation but as soon as the device has completed its scoop movement to fill the paper cup, the ejector spring arm is engaged by a finger of the hand holding the handle 11 and drawn up to eject the cup 10 from the cup 5.

It is evident, from inspection of Figure 3, that instead of rolling an annular bead 8 in the cup 5, use may be made of a wire 22, which may be in the form of a ring and soldered or otherwise 5 suitably secured adjacent the upper, open edge of the cup 5, this ring 22 also providing a support for the rolled edge 9 of the cup 10 to prevent its collapse into the cup 5 against the pressure of the ice when the device is used in its 10 scooping movement.

It is evident, therefore, that I have provided a cup filling device in the nature of a scoop in which may be positioned, a thin paper cup which may be filled without danger of collapsing and 15 which can be quickly removed from the filling device at substantially the same time that the filling movement or operation is completed.

My invention is not to be restricted to the precise details of construction shown since various 20 changes and modifications may be made therein without departing from the scope of the invention or sacrificing the advantages derived from its use.

What I claim is:—

1. A filling device comprising a slotted cup, a handle therefor, an ejector plate in the cup, an ejector arm passing through said slot connecting the handle and the plate, and an annular inwardly turned supporting bead adjacent the open end of said cup for supporting the upper edge of a paper cup to be filled. 80

2. A filling device comprising a slotted cup, a handle therefor, an ejector plate, a spring arm connecting said handle and plate and passing through said slot, and a receptacle supporting inwardly turned bead adjacent the open end of said cup. 85

3. A filling device comprising a slotted cup, a tubular handle therefor, an ejector plate disposed in said cup, a spring arm connecting said handle and plate and passing through said slot, the free end of said arm being positioned in said handle, and a paper cup supporting bead adjacent the upper end of the cup. 90 95
